Ernest Hollings

UNITED STATES PATENT OFFICE.

ERNEST HOLLINGS, OF SALE, ENGLAND.

NUT-BLANK-FORMING MACHINE.

1,287,996.

Specification of Letters Patent. Patented Dec. 17, 1918.

Application filed February 16, 1917. Serial No. 149,120.

To all whom it may concern:

Be it known that I, ERNEST HOLLINGS, a subject of the King of Great Britain, residing at Sale, county of Cheshire, England, 5 have invented new and useful Improvements in Nut-Blank-Forming Machines, of which the following is a specification.

This invention relates to those machines in which a movable striking piece is used to 10 knock off the pressed blank from the face of the ejecting plunger (commonly termed the "snap" or "crown") which usually has a recessed end to give the proper form to one face of the nut blank, and in which recess 15 the nut blank sometimes strongly adheres and is not certainly removed by the usual straight acting knocker off.

I hereafter describe the invention with reference to the accompanying drawings on 20 which Figures 1 and 2 are views at right angles to each other of part of a nut blank making machine showing my improvements. *a* is part of the machine frame, *b* knocker off slide operated in a downward direction by a 25 cam *c* on the shaft *d* which is journaled in the usual way in bearings on the frame *a*. The knocker-off slide *b* is slidably held in position by the retaining plate *m* said plate being secured to the main frame *a* by fixed 30 bolts *n* *n* passing through elongated holes *b* *b* in the slide *b*. The upward return motion of the slide *b* is effected by the large spring *p* which abuts at its upper end against the projecting portion *b*' of the knocker off 35 slide *b*, the lower end of the spring *p* abutting against the projecting portion *m*' of the fixed plate *m*. The rod *q* is secured to the fixed retaining plate *m*, passes loosely through the projection *b*' and serves to re-

tain the large spring *p* in correct working 40 position. To insure certain and clear knocking off of the nut blank from the ejecting plunger I make use of a knocking off piece *e* pivoted at *f* to the knocking off slide *b* in such manner that the striking end *e*' of the 45 knocking off piece is caused to have in addition to its downward movement a movement outward from the ejecting plunger *g* in the die *h* as shown in dotted lines *e* so that the nut blank is knocked outwardly away from 50 the ejecting plunger *g* thus drawing the nut blank sidewise out of the recess *i* in the plunger *g* instead of such nut blank, as hitherto, being forced down at right angles to the plunger. This movement of the 55 knocking off piece may be obtained by a pin and roller *j* attached to the knocking off piece and sliding in an angularly arranged guide *k* on the main frame *a*. *l* is a spring and plunger seated in the knocking off piece 60 *e* the plunger bearing against the slide *b* to prevent vibration of the pin *j* in the guide *k* and insure that the roller *j* runs smoothly on the outer face *k*', of the angular guide *k*; but I do not confine myself to this arrangement except as defined by the appended 65 claim.

I claim:

In a nut blank forming machine, a slide on the fixed die frame adapted to move in 70 guides at right angles to the axis of the blank, a rocking piece pivoted on the slide, one arm of the rocking piece being adapted to bear against the nut blank, and an angularly disposed guide on the fixed die frame 75 engaging with the other end of the rocking piece, substantially as set forth.

ERNEST HOLLINGS.

Copies of this patent may be obtained for five cents each, by addressing the "Commissioner of Patents, Washington, D. C."
